UNITED STATES PATENT OFFICE.

LESTER H. KEIM, OF PASADENA, AND RICHARD E. KLINE, OF ALHAMBRA, CALIFORNIA, ASSIGNEES TO OIL WELL SUPPLY COMPANY, OF LOS ANGELES, CALIFORNIA, A CORPORATION OF CALIFORNIA.

ROTARY DRAW WORKS.

Application filed June 29, 1925. Serial No. 40,415.

This invention relates to drum-driving mechanism, and particularly to the type of drum-driving mechanism employed in the drilling or operation of wells such as oil wells and commonly known as a "draw-works".

With the increase in the average depth at which wells such as oil wells are now being drilled, it has been found that the two-speed drawworks hitherto generally employed does not provide sufficient speed changes for efficiently conducting the drilling operations. Accordingly, the well drilling art now requires a rotary drawworks having three different driving speeds with each engine speed.

An object of the present invention is to provide a simple construction applicable to the drawworks mechanisms now in use and without the necessity of increasing its length, which will adapt the same for developing three driving speeds for the drum with each engine speed.

Another object of the present invention is to provide such drawworks with three driving speeds in a construction so arranged that the lower driving speeds are disposed in close proximity to the drum.

Another object of the present invention is to provide a three-speed rotary drawworks in which each of the different drive connections of the drawworks is provided with a clutch located upon the drum shaft of the drawworks, whereby each of such clutches may be readily provided with a control located at a common point.

Various other objects and advantages of the invention will be apparent from a description of a preferred form of rotary drawworks embodying the invention, for which purpose reference is made to the accompanying drawings, in which a preferred example of a rotary drawworks embodying the invention is disclosed.

In the drawing:

Fig. 1 is a side elevation partially in section; and

Fig. 2 is an end elevation of Fig. 1.

Referring to the drawings, the rotary drawworks there illustrated comprises a drum shaft 1 carrying a drum 2 rigidly keyed thereto. Said drum shaft 1 is mounted by three vertical posts, of which 3 and 4 are end posts and 5 an intermediate post.

The drum 2 is located between the posts 4 and 5. In the upper part of the frame, a line shaft or driving shaft 6 is mounted, its axis being disposed parallel to the axis of the drum shaft 1. Preferably, in order to balance the weight of the posts, the line shaft 6 is mounted upon the opposite side of the posts to that of the drum 1.

In accordance with the present invention, there is provided a low-speed drive connection between the shafts, including a member rigid on one of the shafts and a loose member on the other, with a clutch for driving through the low-speed connection at will.

There is also provided an intermediate-speed driving connection between the shafts including a member rigid upon one of the shafts and a loose member on the other shaft with its corresponding clutch for driving through the intermediate speed at will, and there is also provided a high-speed drive connection between the shafts including a member rigid on one of the shafts and a loose member on the other shaft with its corresponding clutch for driving through the high-speed connection, and there is also provided a means corresponding to each clutch for operating the same independently.

The invention is directed to novel means by which these different drive connections may be incorporated in a rotary drawworks to the best advantage so as to provide a three-speed drawworks without increase in length over that ordinarily required for the two-speed drawworks, and to provide for the simplified control of the different speeds and other devices actuated by the drawworks, and to provide such an apparatus that the load placed thereon will be best distributed and taken upon the different supporting posts of the frame.

To derive such advantages, the apparatus is provided with a low-speed driving member, preferably in the form of a rigid sprocket wheel 7 on the line or driving shaft 6, which is connected by a sprocket chain 8 with an aligning low-speed sprocket wheel 9 which is loose on the shaft 1. The sprocket wheel 9 is adapted to be made rigid with the shaft 1 through engagement with its clutch 10, which clutch is adapted to be operated by a lever 11. The clutch 10 is preferably a kick-out clutch, that is, one adapted to be automatically thrown out of

driving relation if the drum shaft 1 is driven at a rate faster than the sprocket wheel 9. The low-speed drive connection is preferably disposed on the shafts 1 and 6 so that the sprocket wheel 9 is mounted close to one end of the drum 2 and between the drum 2 and adjacent end post 4, and the other end of the drum 2 is mounted closely adjacent the intermediate post 5.

10 The intermediate drive connection of the apparatus is preferably provided by an intermediate-speed sprocket wheel 12 which is connected by a sprocket chain 13 with an aligning intermediate speed sprocket wheel 14 which is loose on the shaft 1, this driving connection being preferably disposed between the intermediate post 5 and the end post 3 and closely adjacent the intermediate post so that both of the lower speed driving connections for the drum 2 are mounted close to the drum.

The high-speed drive connection is provided by a high-speed sprocket wheel 15 rigid on the line shaft 6 and connected by a sprocket chain 16 with an aligning high-speed sprocket wheel 17 which is loose on the drum shaft 1. This high-speed drive connection is disposed between the intermediate post 5 and the end post 3, and preferably closely adjacent such end post 3. The high and intermediate speed drive connections are provided with clutches 18 and 19 respectively, mounted on the drum shaft 1 and between the sprocket wheels 17 and 14, the clutch 19 preferably being of the kick-out type. These clutches 18 and 19 are each provided with a lever 20 connected with a rod 21 with a weight 22 normally maintaining the clutches in the released position, and adapted to be actuated to the closed position by a foot pedal 22, the foot pedals being extended into adjacent operating positions. Each of the sliding parts of clutches 18 and 19 are mounted upon a single bushing on the drum shaft 1 and are adapted for independent operation. The shaft 6 is adapted to be continuously driven by means of a chain drive from an engine or other prime mover and continually running over either sprocket wheel 23 or sprocket wheel 24 rigid with the central part of the line or drive shaft 1.

The rotary drawworks is also provided with means for driving a rotary table of a well, and for this purpose a sprocket wheel 25 is mounted upon the line shaft 6 between the high and intermediate speed sprocket wheels 15 and 12. This sprocket wheel 25 is mounted loose upon the drive shaft 6 and is adapted to be connected to the shaft by a clutch 27. This clutch being of a novel construction, in that it is mounted upon a hub or extension of the sprocket wheel 15, a construction which materially aids in making the apparatus compact and permits the

use of both the rotary drive sprocket wheel 25 and the high and intermediate sprocket drive connections for the drum 2 being located between the intermediate post 5 and end post 3. The clutch 27 is adapted to be operated by a lever 28 connected by a rod 29 to a hand lever 30 extended adjacent the other levers of the apparatus.

The drum 2 is indicated as provided with the usual brake bands 31, these being controlled by a lever 32 of the usual or any preferred construction.

With the drawworks of the construction just described, during normal operation, each of the sprocket chains 8, 13 and 15 are continuously driven during the driving of the driving or line shaft 6. The speed at which the drum 2 is thus actuated is dependent upon which of such driving shafts are made to drive the drum 1, the apparatus being so designed that the drum shaft can be brought to progressively higher speeds by actuation of the drive speed clutches in series, the clutch 10 being first brought into driving engagement to connect the low-speed drive connection with the drum 2, the clutch 19 then being brought into driving connection to connect the intermediate speed driving connection with the drum 2, which operation, accelerating the speed of the drum 2 and drum shaft 1, automatically causes the clutch 10 to kick out. Then the high-speed drive connection can be brought into operation by actuation of the clutch 18, causing the clutch 19 to be kicked out and the drum 2 may then be actuated at the highest speed. It is also seen that by the drawworks herein described, each of the different clutches for the different drive connections are mounted upon the drum shaft 1 in place of part of such clutches being mounted on the drum shaft 1 and part on the drive shaft 6. This permits the operating levers of all of such clutches to be more readily assembled in a common controlled position.

The three-speed drawworks herein described may be readily constructed from the general type of two-speed drawworks hitherto employed simply by the addition of the high-speed drive connection at the end of the drawworks most remote from the drum 2. This drive connection is also added in such a manner as to permit the low and intermediate speed drive connections to be disposed in the closest proximity to the drum 2, and thus provides a drawworks best adapted to handling the higher loads applied thereto when necessary to employ the lower driving speeds.

While the rotary drawworks of this invention is well adapted for accomplishing the purposes and objects thereof, it is to be understood that various modifications in the details of construction of the parts may be

made without departing from the spirit of the invention, and the invention is therefore not limited to the specific embodiment described herein but is of the scope set forth in the appended claims.

We claim:—

1. In a three-speed rotary drawworks, the combination of a frame having end posts and an intermediate post and mounting a drive shaft, a drum shaft on the opposite side of the posts, the drum shaft carrying a drum, and a low-speed drive connection between the drum and adjacent end post, and intermediate and high speed drive connections located between the intermediate post and the other end post, one of said last named drive connections including a sprocket wheel provided with a hub mounting a clutch, and a drive sprocket mounted on the line shaft between the high and intermediate speed drive connections and adapted to be driven by said last mentioned clutch.

2. In a device of the class described, the combination of a driving shaft and a sprocket wheel rigid thereon and a sprocket

wheel loose thereon, the rigid sprocket wheel having a hub, a clutch slidably mounted on said hub and engageable with the loose sprocket wheel to form a drive connection between said sprocket wheel and driving 30 shaft.

3. In a rotary drawworks, a frame having end posts and an intermediate post, a drum mounted upon a shaft carried by the posts and a drive shaft carried by the posts with a drive connection and its clutch between the drum and adjacent end post, and a high and intermediate speed drive connection located between the other end post and intermediate post, each provided with clutches disposed 35 between the drive connections, an additional driving sprocket mounted on the drive shaft between said driving connections, and a clutch mounted on a sprocket wheel of one driving connection for releasably engaging 40 said additional driving sprocket.

Signed at Los Angeles, Cal., this 20 day of June, 1925.
